UNITED STATES PATENT OFFICE

112,874

DESIGN FOR A SHOE SOLE WHITENING PROTECTOR

Thomas C. Crowley, Jackson Heights, Long
Island, N. Y.

Application August 6, 1938, Serial No. 79,153

Term of patent 7 years

To all whom it may concern:

Be it known that I, Thomas C. Crowley, a citizen of the United States, residing at Jackson Heights, Long Island, in the county of Queens and State of New York, have invented a new, original, and ornamental Design for a Shoe Sole Whitening Protector, of which the following is a specification, reference being made to the accompanying drawing, forming part thereof.

Figure 1 is a plan view of a shoe sole whitening protector showing my new design;

Figure 2 is a side elevational view; and

Figure 3 is a perspective view of the same.

The characteristic features of my design for a shoe sole whitening protector are its rectangular shape, two sides of the same being concave and one of which to be a greater depth than the other; one end being straight and the other end being turned up so as to protect the sole of the shoe when the design is in use.

I claim:

The ornamental design of a shoe sole whitening protector, as shown and described.

THOMAS C. CROWLEY.
